TIE PIN OR THE LIKE

John Fontana, 317 Mannheim Road,
Bellwood, Ill. 60104

Filed July 26, 1968, Ser. No. 12,920

Term of patent 14 years

Int. Cl. D2—08

U.S. Cl. D2—431

FIG. 1 is a front elevational view of a tie pin showing my new design;

FIG. 2 is a side elevational view as seen from the right of FIG. 1; and

FIG. 3 is a top plan view thereof.

The essential features of my design reside in the full line disclosure.

I claim:

The ornamental design for a tie pin or the like, as shown and described.
